B. G. CONNER

ADJUSTABLE WINDOW SHADE

Filed June 9, 1925

UNITED STATES PATENT OFFICE.

BENJAMIN G. CONNER, OF LOS ANGELES, CALIFORNIA, ASSIGNOR TO 2-WAY WINDOW-SHADE COMPANY, A CORPORATION.

ADJUSTABLE WINDOW SHADE.

Application filed June 9, 1925. Serial No. 35,920.

My invention relates to window shades and their rollers and pertains more particularly to vertically adjustable shades and rollers for same.

5 The invention has for its principal object the provision of improvements whereby smooth and efficient operation, together with quick installation and permanency of structure will result.

10 Vertically adjustable shades of the type to which my invention relates, include a roller which is mounted in vertically movable brackets; said brackets are carried at the lower end of cords which are wound upon 15 an upper roller carried by fixed brackets or fixtures. Each vertically movable bracket, sometimes termed the mouse, is arranged to be guided by some suitable means to hold the shade and its roller in the plane of the normal path of vertical travel. It is among 20 other objects of the invention to provide for quickly and accurately positioning the guiding means with regard to the upper fixtures and to provide for insuring smooth running 25 and proper winding of the cords over the upper roller.

Other objects include the provision of substantial, neat appearing parts at moderate cost. Still other objects and advantages of 30 my invention will more fully hereinafter appear.

I have illustrated my invention by the accompanying drawings, in which:

Fig. 1 is an elevation of a complete embodiment of my invention in place between the jambs of a window or the like.

Fig. 2 is a section thereof seen on a line 2—2 of Fig. 1.

Fig. 3 is a view in section on a line 3—3 of Fig. 2.

Fig. 4 is a view in section on a line 4—4 of Fig. 2.

Fig. 5 is a perspective view of the lower end of a member hereinafter known as the 45 guide member.

Fig. 6 is a perspective view of a member hereinafter known as the elevating bracket, sometimes spoken of as the mouse.

Fig. 7 is a view in section seen on a line 50 7—7 of Fig. 3.

Fig. 8 is a perspective view of the upper end of the guide member.

Fig. 9 is a view in elevation of the right hand stationary fixture.

Fig. 10 is an elevational view of the left 55 hand stationary fixture for the shade roller.

Fig. 11 is an elevational view of a modified form of one of the brackets for supporting the upper roller.

Fig. 12 is a horizontal sectional view of 60 of a modified form of the shade roller supporting bracket or mouse.

More specifically, in carrying out my invention in the embodiment illustrated, I employ an upper roller 12 carried by the fixtures 9 and 10. Said roller is provided with metallic end members 13 and 14 respectively, which are each arranged to receive a corresponding one of the cords 15 and 16 respectively. Roller 12 is otherwise of usual construction, embodying a spring 17 and a pawl and ratchet. Fixture 9 is provided with an elongated or rectangular slot 18 adapted to receive the flattened pintle 19 of the roller; said pintle being attached to the spring in 70 the customary manner. Fixture 10 is provided with a vertical slot 20 for revolvably holding the round fixed pintle 21. The central part of each fixture, where the slot is provided, is formed to bulge inwardly to 80 provide a dome 22. Slot 20 is intersected by another slot 23, horizontally disposed and continuing thence, parallel to the base of the dome until it terminates by virtue of the contour of said dome. The two fixtures, 85 so slotted provide for mounting the roller by first inserting the flattened pintle in the slot 18, and subsequently inserting the round pintle in the horizontal slot 23 and moving the roller inwardly until said round pintle 90 can be lowered into the vertical slot 20.

The end members 13 and 14, of the roller are fixed as by screws 24. A salient feature of the end member resides in the provision of a curved flange 25. It may be said of each 95 member, for the sake of description, that its end increases in diameter outwardly at a constantly changing rate. Adjacent the extreme outer edge, each of the end members is provided with a small aperture 26 adapted to receive the corresponding cord. Each cord after passing through the corresponding aperture 26 is knotted as at 27. It will be apparent now that as the roller is revolved

in one direction the cords will be wound around corresponding end members. The curved flanges provided at the end of each end member causes the cord to be wound in juxtaposed turns rather than in superimposed turns or convolutions. Obviously, if both cords did not wind in the same manner at all times, one cord would raise its load faster than the other, which in this instance would result in uneven running of the moving parts and inclination of the shade 28 and its customary spring and roller 29.

Each roller end is arranged to fit closely in the corresponding cupped fixture, as shown particularly in Fig. 3, thus enclosing the pintles against the intrusion of dust and ravelings while preventing the cords from ever becoming fouled around an adjacent 20 pintle.

Each fixture is provided with an inturned flange 30, making the body portion of the fixture substantially cup-shaped. The flange is cut away as at 31 for the reception 25 of the cord, and adjacent that point, there is provided an integral lug 32 provided with a slot 33. The fixture is held to the jamb by a screw 33^a. By loosening the screw one turn or less, the fixture may be removed, or 30 secured in place, as the case may be. Each fixture is provided with a depending integral ear 34 arranged to be spaced from but parallel to, the jamb when the fixture is in 35 position. Said ear is of shallow channel cross section.

The shade roller 29 is held by traveling brackets 37, one being carried at the lower end of each corresponding cord, apertures 35 are provided for tying a cord thereto.

A third cord 38 depends from one of the traveling brackets and thereby the upper roller is controlled. Brackets 37 each include notches 39 and 40, respectively; the bracket illustrated having a plurality of slots 41 for both ends of a roller so that such bracket may serve either as right-hand or left-hand bracket. The plurality of notches also provide for changing the elevation of the roller with regard to the bracket. A shade and a roller having a small number of convolutions should be carried by the uppermost set of slots, of a pair of brackets, so that it may be moved up into 50 actual abutment with the upper roller, without permitting the traveling brackets to ride too high.

For each traveling bracket there is provided an elongated guide member 42 of a length corresponding to the vertical travel 60 of the shade roller. Each guide member is of tubular construction of square cross section and is provided with a co-extensive slot 43 in which the corresponding pintle rides and is guided. The interior space 44, 65 enclosed by the walls of the guide member,

receives the corresponding bracket 37 and guides it in its vertical travel. In installing the complete device, the depending ear of an upper fixture is inserted in the upper open end of the corresponding guide member, 70 preferably before the screw 33^a is tightened down. Another screw 45 is located at the lower part of the jamb to secure a lower fastening lug of the guide member. Said lug is provided with a horizontal slot 46. When 75 the upper end of the guide member is connected with the corresponding depending ear, the lower end of the member is moved forwardly under the head of the screw. With the screw 45 disposed in the slot, the 80 assembly of upper bracket and guide member is permanently secured by tightening down the lower screw.

The modified form of bracket illustrated in Fig. 11 is especially designed for use 85 where attachment to the other face of the jamb or parting strip is desirable, and in such construction, the screw-receiving ear or lug 32^a is bent so to occupy a position at right angles to the body of the bracket or 90 fixture.

Obviously, when this form of bracket is made use of, the slotted guides will lie perpendicular with the shade carrying roller thereby making it necessary to provide the 95 traveling bracket or mouse with an extension such as 37^a that receives the pintle of the shade roller (see Fig. 12).

I have found that by providing the fixed pintle 21 with a slight flange or head on its 100 outer end, the end of the roller provided with such pintle cannot become accidentally disengaged from its bearing bracket.

The operation, advantages, and method of assembly of the parts is apparent from the 105 foregoing. As to the actual operation of the device as a whole, it will be seen that with the aid of the lower cord, the upper roller may be turned in either direction and may be stopped at any desired point, as in 110 the case of any common shade. Thus, the elevation of the shade may be changed at will. The shade is wound upon, or unwound from its roller in the usual manner. When the traveling brackets are moving, they are 115 guided by the guide members, and when the shade roller is stationary, the pintles and brackets, being guided by the guide members, hold the shade roller from being moved forwardly by whipping of the shade. The curved flanges provided by the end members of the upper roller, provides for even rolling 120 of both cords and keeps the shade roller always in a true horizontal position.

It will be apparent now that I have provided a device of the class described, in 125 which the shade, shade roller, cords and roller supporting brackets are well guided and governed to produce smooth and efficient operation at all times, together with 130

neat appearance, and while I have shown and described a specific embodiment of my invention, I do not limit myself to any specific construction or arrangement of parts, 5 and may alter same as required, without enlarging the scope of my invention, within the appended claims.

I claim as my invention:

1. An adjustable window shade comprising a roller, pintles projecting from the ends thereof, fixture plates in which said pintles are mounted, a slotted ear projecting from each plate, which ear is adapted to receive an attaching screw an off-set ear depending 15 from each plate, a channeled guide member having its upper end embracing the depending off-set ear of each plate, the lower end of each guideway being provided with a screw receiving slot, runners arranged for sliding 20 movement in the channeled guideways, cords secured to said runners and to the end portions of said roller, a cord secured to and depending from one of said runners and a shade carrying roller having its pintles engaged in said runners.

2. In an adjustable window shade, a roller, pintles projecting from the ends thereof, tubular members projecting from the ends of said roller, the outer portions of which tubular members are flared outwardly, fixture plates having flared edges that enclose the flared edges of the tubular members on said roller, said fixture plates being provided with apertures that receive the pintles in the 30 ends of said roller, a slotted ear projecting from each fixture plate, which slotted ear is adapted to receive an attaching screw, an off-set ear depending from each fixture plate to one side of the center thereof, channeled 35 guideways having their upper ends embracing the off-set ears on said fixture plates, the lower ends of said guideways being provided with screw receiving slots, runners arranged for sliding movement in the channeled guideways, cords having their lower ends connected to said runners and their upper ends 40 connected to the outwardly flanged portions 45

of the tubular members on the ends of said roller and a shade carrying roller arranged between and supported by said runners.

3. In an adjustable window shade, a pair of fixture plates, a slotted ear projecting from the lower portion of each plate for the reception of an attaching screw, an ear depending from each fixture plate, said ear 50 being off-set relative to the center of said plate and relative to the vertical plane occupied by the body of the plate, channeled guideways having their upper ends embracing the off-set ears on said fixture plates, the 55 lower ends of said guideways being provided with screw receiving slots, a roller provided in its ends with pintles that are journaled in said fixture plates, cords secured to the ends of said roller and depending therefrom, 60 which cords pass through the slotted guideways, runners arranged for sliding movement in the channeled guideways and connected to said cords and a shade roller provided in its ends with pintles that are 65 mounted in said runners.

4. In an adjustable window shade, a fixture plate comprising a disk, a curved flange encircling a substantial portion of the edge of said disk, a slotted ear projecting from 70 the lower portion of said disk and an ear depending from said disk, which ear is off-set with respect to the center of the disk and with respect to the vertical plane occupied by the body of the disk.

5. In an adjustable window shade, a fixture plate comprising a disk, a curved flange encircling a substantial portion of the edge of said disk, a slotted ear projecting from the lower portion of said disk, an ear depending from said disk, which ear is off-set 75 with respect to the center of the disk and with respect to the vertical plane occupied by the body of the disk, a dome-shaped projection at the center of said disk and which 80 dome-shaped projection is provided with a pintle receiving aperture.

In testimony whereof I affix my signature.
BENJAMIN G. CONNER.
